UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,398, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The figure in the accompanying drawing represents sufficient of a shawl-pattern to illustrate my design, the features of which are the alternate wide and narrow stripes, A and B, the latter being composed of a plain center, *a*, and of a border made up of narrow parallel ribs *b c d*, &c., of the character shown, and of different shades or colors.

The stripe A is composed of a great number of minor parallel stripes, bars, or ribs, of

varying widths, as shown in the drawing, and different shades or colors, some of these bars being blended or shaded into each other, this being especially noticeable at the edge *h* of the stripe.

Irrespective of the colors employed, I claim—

1. The design for the stripe A, as represented.
2. The design for the whole pattern, including the stripes A and B.

In testimony whereof I have signed my name to this specification in the presence of two subscribing witnesses.

FRED. WINK.

Witnesses:

WM. A. STEEL,
HUBERT HOWSON.
